UNITED STATES PATENT OFFICE.

JAMES F. CHESEBRO, OF KNOXVILLE, TENNESSEE.

DESIGN FOR AN INHALER-TUBE.

SPECIFICATION forming part of Design No. 19,128, dated June 4, 1889.

Application filed February 11, 1889. Serial No. 299,524. Term of patent 14 years.

To all whom it may concern:

Be it known that I, JAMES F. CHESEBRO, a citizen of the United States, residing at Knoxville, in the county of Knox and State of Tennessee, have invented and produced a new and original Design for an Inhaler-Tube, of which the following is a specification, reference being had to the accompanying drawings, forming part thereof.

Figure 1 is a vertical sectional view of an inhaler-tube embodying my design. Fig. 2 is a cross-section of the same.

Referring to the drawings, D indicates the inhaler-tube.

The leading feature of my design consists in the cylindrical enlargement E of the tube

D and the central tube F within said enlargement E and joining at its lower end the lower portion of said tube D, and having at its upper end the tapering bulb G, situated in said enlargement E.

What I claim is—

The design for an inhaler-tube herein described, and shown by the accompanying drawings.

In testimony that I claim the foregoing as my own I have hereto affixed my signature in presence of two witnesses.

JAMES F. CHESEBRO.

Witnesses:

MOSES GREER, Jr.,

WILLIAM P. GRIFFIN.
